(57) CLAIM

I claim the ornamental design for a hat, as shown and described.

DESCRIPTION

FIG. 1 is a perspective view of a hat, showing my new design; FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof;

FIG. 8 is a front elevational view thereof, illustrated with front flaps thereof in a lowered position; and

FIG. 9 is a front elevational view thereof, illustrated with the front flaps in a lowered and tucked position;

FIG. 10 is an enlarged top plan view of a main body in a flat orientation, a central drawstring, a main body stabilizer, a front bill stabilizer, and a rear bill omitted for clarity of illustration;

FIG. 11 is an enlarged top plan view of the main body stabilizer in a flat orientation, the central drawstring, main body, front bill stabilizer, and rear bill omitted for clarity of illustration;

FIG. 12 is an enlarged top plan view of the front bill stabilizer in a flat orientation, the central drawstring, the main body, main body stabilizer, and rear bill omitted for clarity of illustration; and

FIG. 13 is an enlarged top plan view of the rear bill in a flat orientation, the central drawstring, the main body, main body stabilizer, and front bill stabilizer omitted for clarity of illustration.

The broken lines showing a person in FIG. 1 depict environmental matter and form no part of the claimed design. The remaining broken lines represent stitching, and are part of the claimed design. The top plan views of FIGS. 10-13 are understood to be mirror images of the corresponding bottom plan views, the thickness of the elements shown in such views when in the flat configuration understood to be the thickness of the material used and depicted in the other views.
